UNITED STATES PATENT OFFICE.

STUART OTTO AND JACK CARL JANKUS, OF SCRANTON, PENNSYLVANIA; SAID JANKUS
ASSIGNOR TO SAID OTTO.

ABSORBING STILL FOR REFRIGERATING APPARATUS.

Application filed January 10, 1923. Serial No. 611,810.

To all whom it may concern:

Be it known that we, STUART OTTO and JACK CARL JANKUS, both citizens of the United States, and residents of Scranton, in the county of Lackawanna and State of Pennsylvania, have invented certain new and useful Improvements in Absorbing Stills for Refrigerating Apparatus, of which the following is a specification.

10 In the type of refrigerating apparatus to which this invention relates there is provided a receptacle adapted to act alternately as a still and as an absorber. When serving as a still the contents are heated so that refrigerant gas is driven off from the liquid, delivered to a condenser where it is cooled and liquefied under pressure, and then delivered to a receiver or evaporator. When 15 the refrigerant gas, or the desired part thereof, is thus separated and liquefied, the heat is shut off, and the liquid remaining in the still is cooled or permitted to cool, whereupon it reabsorbs the gas, causing a reduction in pressure, an evaporation of the liquefied gas in the evaporator, and the desired 20 cooling or refrigerating effect by reason of such evaporation. When the liquefied gas has evaporated and been reabsorbed, the heating of the receptacle is begun again. 25 The length of the successive heating and cooling periods may be controlled automatically or manually as desired, and in accordance with the details of construction, proportions of the parts, cooling effect to be 30 produced, etc.

In order that the distilling operation may be satisfactorily carried on, it is desired that the outlet for the gas be at a point above the liquid level, while to secure the most satisfactory absorbing action it is important that the returning gas be delivered to the lower part of the body of the liquid. This deep delivery causes a circulation of the liquid due to the difference in specific gravity of 45 the lighter strong liquor freshly formed at the point of gas delivery and the upper heavier weak liquor. It also better insures complete absorption of the gas before it can escape from the liquid at the upper surface 50 of the latter.

Various schemes have been proposed to accomplish this result. It has been proposed that the gas pipe have separate branches controlled by valves to insure flow through

a branch leading from the top during the 55 heating operation, and through a branch leading to the bottom during the cooling or absorbing operation, but positively actuated valves are hard to keep properly packed against leakage to or from the atmosphere 60 under the varying pressures, and automatic check valves often fail to close gas-tight, due to particles of scale or other solid matter lodging on the seating surface.

The main object of this invention is to 65 provide an improved construction in which returning gas is delivered adjacent to the bottom of the absorption chamber but all valves for controlling the gas flow to or from the absorbing still are eliminated, and 70 the desired delivery and return of the gas insured without the use of any moving parts whatsoever.

A further object of our invention is to 75 provide an improved construction whereby vapors produced by the evaporation of the liquid in the still are cooled and condensed before leaving the still, so that the gas leaving the still during the heating period is 80 substantially dry, and there is little or no loss of the absorbing liquid from the still.

A further object is to provide a double 85 compartment construction in which substantially all of the liquid is automatically transferred back and forth from one compartment to the other, and the distilling operation takes place while the liquid is in one compartment and the absorbing operation while the liquid is in the other compartment.

A further object is to secure the automatic 90 transfer of the liquid solely by the effect of the proper changes in temperature and pressure which are produced to accomplish the distilling and absorbing operations. Other 95 objects and advantages of our improved construction will be pointed out hereinafter, or will be apparent from a consideration of the specific forms illustrated in the accompanying drawings.

In these drawings:

Fig. 1 is a vertical section through a device constructed in accordance with our invention, and

Figs. 2 and 3 are similar sections of other forms which the invention may assume.

In the construction illustrated in Fig. 1 there is provided a receptacle 10 subdivided into two compartments 11 and 12 by means

of a partition 13. The compartment or chamber 11 serves as the absorbing chamber, and the compartment or chamber 12 as the main distilling chamber. The sole means of communication between these chambers is conduit means shown as a pipe 14, one end 15 of which is near the bottom of the chamber 12, and the other end 16 of which is in the form of a perforated head adjacent to the bottom of the chamber 11. The pipe passes through the partition 13 at a point above the normal liquid level in the chamber 11.

The absorbing chamber 11 is provided with any suitable means for cooling it during the absorbing action. This is illustrated as a cooling coil 17 through which water or other cooling medium may circulate and the flow of which may be controlled in any suitable manner, as for instance by manually or automatically operated valves, not shown.

For heating the liquid during the distilling period, any suitable form of heating means may be employed. In the construction illustrated the two chambers 11 and 12 are side by side, and the partition 13 is substantially vertical. Beneath the two chambers there may be a gas burner 18, and extending horizontally through both chambers adjacent to the lower portion thereof, there may be an open-ended tube 19 within which one or more electric heaters or resistance units 20 may be inserted. By using two such resistance units longitudinally movable within the tube 19, the main heating effect may be produced in the portion of the tube within the chamber 12 or in the portion of the tube in the chamber 11, or the heating effect may be distributed equally. This electric heating may be employed in addition to the gas heating, or either form of heating may be employed to the exclusion of the other.

The sole gas connection for the refrigerant gas is at the upper part of the chamber 12, and is shown in the form of a pipe 21 which leads to the condenser or other part of the system. In the upper part of the chamber 12 above the normal liquid level but below the end of the pipe 21, there is provided means for drying the refrigerant gas by condensing out from it the steam or water vapor resulting from any partial evaporation of the absorbing liquid. This is illustrated as a pair of superposed cooling coils 22 and 23 with perforated partitions 24, 25 and 26. The perforations are so located that the gas and any water vapor which may accompany it, is directed against the surface of the cooling coils. Any suitable cooling fluid may be caused to circulate through these coils during the distilling period, and may be automatically or manually controlled by any suitable form of valves, not shown.

In the operation of the construction illustrated the receptacle is filled through any suitable filling opening (not shown) to the desired level with water or other absorbing liquid, the quantity being somewhat less than enough to fill one of the two compartments. It will be noted that the only outlet from the chamber 11 is through the pipe 14 which leads from near the bottom of this chamber. Therefore during the heating period the gas distilled off from the liquid in the chamber 11 will cause a gas pressure above the surface of the liquid which will force substantially all of the strong liquor through the pipe 14 into the chamber 12 where the pressure is lower, due to the fact that this chamber 12 has an outlet 21 to the condenser. As long as the heating action continues, the main body of the liquid will remain in the chamber 12, and the gas driven off therefrom will be cooled by the coils 22 and 23 sufficiently to condense out the steam or water vapor but permit the remaining gas to go out through the pipe 21 to the condenser. When all of the absorbed gas has been driven off and liquefied, or when the heating operation has been continued for the desired length of time the supply of heat is shut off and a cooling fluid is caused to circulate through the coil 17. The reduction in temperature in the chamber 11 results in a corresponding reduction in gas pressure, and the partial vacuum will suck substantially all of the weak liquor back through the pipe 14 from the chamber 12. Thereafter, as the gas continues to return through the pipe 21 from the evaporator, it will enter the chamber 12 which is now substantially free from liquid, and will pass through the pipe 14 and escape through the small holes in the head 16 and be absorbed by the liquid. It will thus be noted that during the distilling period the liquid is in the chamber 12, and the gas may freely escape therefrom and pass through the pipe 21 leading from a point above the liquid level, while during the absorbing period the main body of the liquid will be in the chamber 11 and the gas will enter this liquid by passing through the pipe 14 terminating in the lower part of the body of the liquid. Thus, proper operation is secured without the use of any valves or other moving parts for controlling the flow of the gas, and insuring the delivery to and from the liquid.

The construction illustrated in Fig. 2 is similar in many respects to that above described. The main difference is that the two chambers 11^a and 12^a are superposed rather than being disposed side by side, and the partition 13^a is substantially horizontal rather than vertical. The pipe 14^a leads from a point near the bottom of the upper chamber 12^a to the perforated distributing head 16^a near the bottom of the absorbing

chamber. In this form we have illustrated a plurality of heating units which may be operated simultaneously or independently. A gas burner 18^a is shown beneath the lower compartment, and electric heating units 20^a are located in the lower part of the absorbing chamber. Additional heating units 20^{aa} are mounted in the distilling chamber 12^a near the lower portion thereof. To effect a more rapid transfer of the liquid from the absorbing chamber to the distilling chamber at the beginning of the heating or distilling operation, heating units 28 may be employed in the upper part of the absorbing chamber. As the heating units 20^{aa} and 28 are near the partition 13^a either may be used to the exclusion of the other heating units. When the heat is turned on to the units 20^{aa} enough heat will be transmitted to the lower chamber to effect a gas pressure therein sufficient to force the liquid to the upper chamber.

Other means might be employed for heating the liquid in the chamber 11^a or by heating the gas above the liquid level in this chamber to cause the rapid transfer of the liquid through the pipe 14^a to the upper chamber, and the driving off of the gas which is then dried by the cooling coils 22^a and 23^a, and conducted to the condenser through the pipe 21^a. When the supply of heat is shut off the drop in temperature and pressure in the chamber 11^a will cause the rapid return of the liquid to the lower chamber, and thereafter the gas will flow down through the pipe 14^a and be absorbed by the liquid at the distributing head 16^a, the liquid being cooled by the cooling coil 17^a.

40 The form shown in Fig. 2 is in many respects the preferred one as the superposed arrangement of the chambers causes gravity to assist in the return of all the liquid to the lower chamber at the beginning of the absorbing period.

45 In the construction shown in Fig. 3, the same principle of operation is employed. By making the absorbing chamber 11^b substantially dome-shaped the distilling chamber 12^b has a portion which is disposed above the absorbing chamber as in Fig. 2, and also has an annular part which is disposed alongside of or encircling the absorbing chamber. The pipe 14^b is of siphon form as in Fig. 1, and extends from near the bottom of the chamber 12^b to near the bottom of the chamber 11^b. Only one heating unit is illustrated, that being a gas burner 18^b, beneath the absorbing chamber. The heat from this in passing up along the sides of the lower part of the distilling chamber 12^b, will serve to effectively heat the distilling chamber, although additional heating units may be employed for direct heating of the distilling chamber. It is thought that the construc-

tion of the parts and the operation will be clear from the drawing and from the foregoing description.

50 Although the pipe 21 constitutes the only normal inlet and outlet for gas to and from the receptacle, an additional inlet pipe may be provided. After long continued operation liquid which is not readily vaporizable at the temperature of the evaporator may accumulate therein. A pipe leading from the bottom of the evaporator may connect with the absorbing chamber. Such a pipe 30 with a normally closed valve 31, is shown in Fig. 2, and a similar one may be used in the forms shown in Figs. 1 and 3. When liquid 55 from the still, or other liquid not readily vaporizable, accumulates in the evaporator, a valve in the pipe 21 may be closed and the valve 31 opened shortly after the end of the boiling period. The decreasing gas pressure 60 in the cooled absorber, and a high pressure remaining in the evaporator, will force such liquid from the lowest part of the evaporator back to the absorber. The valves may then be returned to their normal positions.

65 Although the conduits 14, 14^a and 14^b are shown and claimed as the sole inlets and outlets of the chambers 11, 11^a and 11^b respectively, it will of course be obvious that ordinary filling and draining openings might be 70 used but they would remain closed while the apparatus is in use.

Having thus described our invention, what we claim as new and desire to secure by Letters Patent is:

75 1. An absorbing still for refrigerating apparatus including two chambers, one adapted to serve as the main distillation chamber and having means for the admission and escape of the refrigerant gas and the other adapted to serve as an absorption chamber, and means affording communication between the two chambers, said means having orifices adjacent to the bottom of each chamber, said absorption chamber having no other inlet or outlet, whereby during the heating of the still substantially all of the strong liquor is forced out of the absorption chamber through said communication means to the distillation chamber by the accumulation 80 of gas pressure in the absorption chamber above the said orifice which forms the inlet and outlet of said chamber, and the gas is thereafter distilled off from the liquid while in the distillation chamber, and whereby upon the cooling of the still and reduction of gas pressure in said absorption chamber weak liquid is returned to said absorption chamber through said communication means and the gas thereafter delivered through said communication means to the lower part of the liquid in the absorption chamber.

85 2. An absorbing still for refrigerating apparatus including an absorption chamber,

a distillation chamber, means affording communication between the two chambers, said means terminating adjacent to the bottom of one chamber and having an orifice adjacent to the bottom of the other chamber, there being no other communication between the chambers, said distillation chamber having means for the admission and escape of the refrigerant gas to and from the still, means for heating the still to effect a transfer of substantially all of the liquid through said communication means to the distillation chamber, and means for cooling the still to effect a return flow of the liquid through said communication means.

3. An absorbing still for refrigerating apparatus including a vessel having a partition subdividing it into an upper distillation chamber and a lower absorption chamber, and conduit means having one end terminating adjacent to the bottom of one of said chambers, and the opposite end opening into the other chamber adjacent to the bottom thereof, said conduit means constituting the sole inlet and outlet to the lower chamber, the upper chamber having means for the admission and escape of the refrigerant gas.

4. An absorbing still for refrigerating apparatus including a vessel having a partition subdividing it into an absorption chamber and a distillation chamber, conduit means extending from one chamber to the other and having no orifice in the absorption chamber except adjacent to the bottom of the latter and having an orifice in the distillation chamber adjacent to the bottom thereof, said conduit means constituting the sole inlet to and outlet from the absorption chamber, and the distillation chamber having a gas inlet and outlet, means for heating the still whereby there is effected a transfer of substantially all of the strong liquor through said conduit means to said distillation chamber and the distillation of gas from said liquor, and means for cooling the still whereby there is effected a return flow of the weak liquor through said conduit means to said absorption chamber and the later delivery of gas through said conduit means to the lower part of the liquor.

5. An absorbing still for refrigerating apparatus including a pair of chambers, a conduit having its ends adjacent to the bottoms of said chambers respectively, and constituting the sole inlet and outlet for one chamber, a gas inlet and outlet for the other chamber, means for heating the still to effect a transfer of substantially all of the strong liquor from the first mentioned chamber to the second mentioned chamber through said conduit, and means for cooling the still to effect a return flow of the weak liquor to said chamber.

6. An absorbing still for refrigerating ap-

paratus, including a vessel having a partition subdividing the same into two compartments, a conduit having one end adjacent to the bottom of one chamber and the other end provided with a perforated distributing head within the other chamber adjacent to the bottom thereof, means for applying heat to the still adjacent to said partition, and means for cooling the still, said first mentioned chamber having means for the admission and escape of the refrigerant.

7. An absorbing still for refrigerating apparatus including a vessel having a partition forming two superposed chambers, conduit means having one end opening into the lower part of the lower chamber and the other end opening into the lower part of the upper chamber, and constituting the sole inlet and outlet to the lower chamber, means for the admission and escape of refrigerant gas to and from the upper chamber, and means adjacent to said partition for heating the still.

8. An absorbing still for refrigerating apparatus including a vessel having a partition subdividing it into an absorption chamber and a distillation chamber, conduit means leading from near the bottom of one chamber to near the bottom of the other to afford communication between said chambers and constituting the sole inlet and outlet for the absorption chamber, means for the admission and escape of refrigerant gas from the distillation chamber, and means closely adjacent to the bottom of the distillation chamber for heating the liquid and driving off the gas and at the same time maintain sufficient gas pressure in the absorption chamber to prevent the retention of any substantial amount of liquid in the latter during the action of said heating means.

9. An absorbing still for refrigerating apparatus, including a vessel having a partition therein subdividing the same into two chambers, one serving as a distilling chamber and having a gas inlet and outlet, and the other serving as an absorber and having conduit means leading from the bottom thereof nearly to the bottom of the first mentioned chamber, and independent means for cooling each of said chambers, the cooling means in the first mentioned chamber being in the upper part thereof.

10. An absorbing still for refrigerating apparatus including a pair of superposed chambers, conduit means having one end opening into the lower part of one chamber and the other end opening into the lower part of the other chamber, and constituting the sole gas inlet and gas outlet for the lower chamber, means for the admission and escape of the refrigerant gas to and from the upper chamber, and a normally closed liquid return pipe communicating with the lower chamber.

11. An absorbing still for refrigerating apparatus including a vessel having a partition forming two superposed chambers, conduit means having one end opening into the lower part of the lower chamber and the other end opening into the lower part of the upper chamber, and constituting the sole inlet and outlet to the lower chamber, means for the admission and escape of the refrigerant gas to and from the upper chamber, means for heating the still, and means in the upper portion of the upper chamber for cooling the gases driven off during the heating of the still to condense water vapor therefrom. 45
12. An absorbing still for refrigerating apparatus including a vessel having two partitions therein subdividing the same into three chambers, means affording communication between two of said chambers, said means extending from the lower part of one to the lower part of the other, there being no other inlet or outlet for one of said two chambers, and means establishing communication between the other of said two chambers and the third chamber, said third chamber having means for the admission and escape of the refrigerant gas to and from the still. 50
13. An absorbing still for refrigerating apparatus including three chambers, means affording communication between two of said chambers, said means extending from the lower part of one to the lower part of the other, there being no other communication between said two chambers, and means establishing communication between one of said two chambers and the third chamber, said third chamber having means for the admission and escape of the refrigerant gas to and from the still, means for heating the still to effect a transfer of liquid through said first-mentioned communication means in one direction, means for cooling the still to effect a return flow of liquid through said first-mentioned communication means, and means associated with said third chamber for cooling the gas to separate out water vapor. 55
14. An absorbing still for refrigerating apparatus including three superposed chambers, means affording communication between the lower and the middle chambers, said means extending from the lower part of one to the lower part of the other, there being no other communication between said two chambers, and means establishing communication between the middle chamber and the upper chamber, said upper chamber having means for the admission and escape of the refrigerant gas to and from the still. 60
15. An absorbing still for refrigerating apparatus, including a vessel having a pair of transverse partitions, a port serving as a gas inlet and outlet above the upper partition, said upper partition being perforated, a conduit leading from the lower portion of the chamber between said partitions to the lower portion of the chamber below the lower partition and terminating in a perforated distributor head, said conduit serving for the delivery of liquid from the lower chamber to the middle chamber upon the heating of the lower chamber, and serving for the return of said liquid to the lower chamber, and the delivery of gas to the liquid below the surface of the latter upon the cooling of the lower chamber. 65
